STRIPE MATCHING MACHINE

Daniel Varney Thompson, Ipswich, Mass., assignor, by mesne assignments, to Tubular Textile Machine Corporation, Woodside, N. Y., a corporation of New York

Application February 19, 1952, Serial No. 272,483

6 Claims. (Cl. 26—51.5)

This invention relates to improvements in stripe matching machines. More particularly, the invention is concerned with an automatic registering mechanism for such machinery.

Transversely striped goods produced on circular knitting machines is produced in tubular form and requires splitting longitudinally and stitching the split edges back together in order to produce goods in which the courses and wales are properly disposed at right angles to each other and each stripe is a continuous band running around the tubular fabric.

Narrow striped material may have the stripes running helically so that in a piece of goods having a repeated pattern including, for example, blue, green, red and yellow stripes, a stripe of each color will be a continuous helix running the full length of the goods. Such material requires splitting, displacing one split edge with reference to the other by the width of the complete pattern of stripes which is duplicated along the fabric and then sewing the goods together again with the stripes matching, so that the piece is converted from one having helical stripes running its full length to one having a succession of stripes, each of which is a band running completely around the fabric tube.

In wider striped material, the stripes may not be helical but the change from one color yarn to another creates a longitudinal strip in the goods where the yarn color is changed. Each stripe as it enters this strip being displaced longitudinally of the tube with reference to the same stripe as it continues on the other side of the strip and there being also certain other irregularities in the stitch formation in this strip, such goods requires to be split along the strip where the color changes are effected and to have the stripes brought back together and stitched in registry to produce the desired regular fabric.

Machinery for effecting the required stripe matching is well known and has generally been operated manually so far as making the required adjustment for bringing the stripes into registry before stitching the split fabric tube back together again.

As will be apparent in the following description, photo-cell registry control systems of usual and known type are not adaptable to stripe matching of knitted goods.

It is an object of the invention to provide a photo-electrically controlled registration mechanism for stripe matching of such knitted goods.

A further object of the invention is to provide a registering system capable of operating on a variety of fabrics having stripes of various colors and of various widths arranged in a variety of different orders, without necessitating complicated or delicate adjustments in the registering mechanism.

A still further object of the invention is to provide a registering system of stripe matching capable of operating on simple belt drives and not requiring complicated differential or other gearing.

With the foregoing objects as well as others which will appear in the following description in mind, a ma-

2

chine embodying the invention in a preferred form will now be fully described with reference to the accompanying drawing and the features forming the invention will then be specifically pointed out in the appended claims.

5 In the drawing:

Figure 1 is a floated schematic isometric view of a stripe matching machine embodying the invention in a preferred form;

10 Figures 2 and 3 are, respectively, isometric views of a section of tubular knitted fabric before and after matching of the stripes;

Figure 4 is a plan view of the mechanism of Figure 1; and

15 Figure 5 is a schematic circuit diagram of the control system employed with the photoelectric scanning devices used for matching the stripes.

20 Referring now to Figures 1 and 2, a generally conventional stripe matching machine is shown, the tubular knitted fabric F to be matched is supplied from a roll 1, being fed by driven roller 2 and cooperating idle roller 3, being conditioned by a steam cylinder 4 and then passing over the usual spreader at 5, which element is supported by a stud shaft 6 and also rests upon a driven roller 7, and cooperates with a slitter wheel 8, as indicated. The slit fabric now passes between rollers 9 and 10, after which the slit edges are separated as shown, the fabric being spread apart to form upper and lower courses adjacent the slit edges. The upper course passes over an idle divider roller 11, between this roller 11 and a driven drive roller 12 cooperating therewith, while the lower course passes over a second divider roller 13.

25 The two courses come together again on idle roller 14, passing between driven roller 15 and idle roller 16, after which they are again separated, passing over the air tubes 17 and 18 to straighten the two edges of the cloth preliminary to stitching, in the usual way. The two edges are again brought together at the sewing head, indicated schematically at 20, which serves in the usual manner for stitching the edges together and trimming the edges beyond the stitch line. The trimmed off edges pass between driven and idle drag rollers 21 and 22 into a box or other suitable container 23, while the stitched fabric continues on between driven and idle rollers 24 and 25, up over roller 26 and through the doffer or folder rolls 27, 28, from which it passes into a receptacle 29. Between rolls 14 and 15 is a spreader plate 30, for separating the two courses of fabric, and an upper photoelectric scanning head 31 and lower photoelectric scanning head 32 for reading the stripes in the upper and lower courses of the fabric at this point. Between the sewing head 20 and rollers 24 and 25 is an inspection spreader 33 floated within the fabric tube for permitting examination of the matching of the stripes.

30 As indicated in Figure 4, the slitter disc 8 may have its own separate drive motor, the remainder of the driven rollers may be driven by a suitable pulley drive and cross shafting from a common motor 34, and a separate drive motor 35 is provided for the roller 12.

35 A striped fabric in which the pattern may run spirally, as indicated in Figure 2, is fed into the machine manually in the usual way and the slit edges are displaced with relation to each other so as bring them into or close to a matching relationship, such as indicated in Figure 3.

40 To permit variation in the length of the two courses of the fabric approaching roller 14 for producing such registry, the divider roller 13 is mounted on a stub shaft 36, which is carried eccentrically by a shaft 37, the angular position of which may be regulated by a worm wheel and worm and crank arrangement 38 (Figure 4) for adjusting the position of roller 13 as indicated by the broken arc 40 in Figure 1. After the threading and preliminary manual registration of the fabric, the machine drive is

turned on and thereafter the registration is accomplished automatically by the mechanism now to be described.

The scanning heads 31 and 32 may be of conventional type, available commercially for such purpose as cut-off register control, and may be designed to respond either to a decrease in light intensity or an increase in light intensity, as desired, it being indifferent which operation is selected, but it will be assumed for definiteness that the scanning heads and associated circuits respond to a decrease in illumination.

As indicated schematically in Figure 5, motor 34 is a thyratron controlled in a known and usual way, having a field F34 energized from a suitable power source, not shown, and armature A34 supplied with current from a thyratron control of usual type indicated schematically at THY-1. The current supplied is regulated by the motor speed control, balancing an adjustable voltage against the voltage induced in field f34 of the motor, so that the speed of motor 34 corresponds to the set voltage in the motor speed control. The speed ratio corresponding to a given motor speed control setting may be adjusted by means of potentiometer 58, in which the control voltage for the thyratron control unit is developed. The control voltage applied to the thyratron control unit THY-1 is also applied across potentiometer 51, so that a desired and adjustable fraction of this voltage may be applied to thyratron control unit THY-2, supplying current to armature A35 of the motor 35. This motor may be identical in construction to the motor A34 and has a field F35 energized similarly to the field F34. Field f35 of the motor A35 is, however, utilized for further varying the speed of the motor 35 about the value preset by adjusting potentiometer 51.

The current in field f35 is regulated according to the scanning head readings, as indicated.

The signals S31 and S32, developed in the scanning heads 31 and 32, pass to an electronic time discriminator, which may be of any desired type, such as a four triode bridge circuit for comparing the signals and producing an output error signal proportional to the lead of the signal pulses received from one of the scanning heads as compared to the other. For definiteness, it may be assumed that a positive error signal is produced when the stripes reaching scanning head 31 lead the corresponding stripes reaching the scanning head 32, and a negative signal when the reverse occurs. The error signal is now fed to an error signal integrator and amplifier, which supplies current to the field f35 of motor 35 for varying the speed of this motor.

Variation in the speed of motor 35 varies the speed of rotation of the driven roller 12 cooperating with divider 11, thus varying the tension on the upper course of the fabric. If the stripes reaching scanning head 31 lead the stripes reaching scanning head 32, the current in field f35 will change so as to decrease the speed of motor 35 and roller 12, thus slowing down the upper course of the fabric until registration is restored. Conversely, if the stripes reaching the scanning head 31 lag behind the stripes reaching the scanning head 32, the current in field f35 will be altered to speed up the roller 12, thus reducing the tension on the upper course of the fabric and permitting it to advance until registration is again restored.

The error signal integrator and amplifier, indicated in Figure 5, may have a suitable resistance network for integrating the error signal and which may be adjusted to any desired value, the time constant being selected so as to produce the required accuracy of registration without hunting. Since a system of the character indicated may operate to eliminate error exponentially, overshooting and hunting is readily avoided without sacrificing speed of response, providing that a small dead zone exists.

Since stripe registration within a sixteenth of an inch or so is close enough for all practical purposes, the registering system may operate with a small dead zone,

and any tendency to hunt or overshoot in making required corrections is easily avoided.

It will be observed that the register control system of the present invention differs markedly from usual systems, in that the time of arrival of a stripe at a scanning head is not controlled with reference to the position of any machine element, as, for example, with reference to the angular position of one of the rollers. The registering system is, therefore, enabled to work with a stripe matching machine having belt drive as shown, even though there may be a certain amount of slip and consequent variation in angular position of the various rollers. It is also to be noted that the time of arrival of the stripes at the scanning heads may be quite variable, in view of the relatively great elasticity or stretch of the knitted goods. Since, however, one course of fabric is being compared with another, no difficulty is experienced due to variation in the stretch of the fabric.

It should also be noted that the stripe matching machine may be called upon to match fabric in which the width of stripe, number of different colors and the colors themselves may be varied almost without limit. The photocell scanning mechanisms will, as usual, exhibit a difference in response to different colors. The time discriminator may, however, readily be designed so as to ignore difference in amplitude of the signals from the scanning heads and the averaging of the signals prior to amplification and feeding to the field f35 permits a wide range of variation in stripe width, number of colors and the colors involved without affecting the operation adversely.

What is claimed is:

1. In a stripe matching machine having means for slitting a tubular fabric along one side and rejoining the slit edges together for matching stripes, and including rolls for advancing the slit fabric to the rejoining means, and in combination, a separator plate for separating an upper and lower course of the slit tubular fabric as it passes to the rejoining means, a pair of photoelectric scanning heads responsive to the passage of the stripes on the two sides of the separating plate, a control circuit responsive to the scanning heads for producing an error signal corresponding to the lead of the stripes on one side of the separating plate as compared with those on the other, and means controlled by the control circuit for varying the tension on one of the said courses to register the stripes.

2. In a stripe matching machine having means for slitting a tubular fabric along one side and rejoining the slit edges together for matching stripes, and including rolls for advancing the slit fabric to the rejoining means, and in combination, a separator plate for separating an upper and lower course of the slit tubular fabric as it passes to the rejoining means, a pair of photoelectric scanning heads responsive to the passage of the stripes on the two respective sides of the separating plate, a control circuit responsive to the scanning heads and including a time discriminator for producing an error signal corresponding to the lead of the stripes on one side of the separating plate as compared with those on the other, and means controlled by the control circuit for varying the tension on one of said courses to register the stripes.

3. A stripe matching machine according to claim 2, in which the control circuit also comprises means for integrating the discriminator output for producing an error signal corresponding to the average lead over a predetermined time interval.

4. In a stripe matching machine having means for slitting a tubular fabric along one side and rejoining the slit edges together for matching stripes, and including rolls for advancing the slit fabric to the rejoining means, and in combination, a tension control roller, operatively engaging a course of the slit tubular fabric, a tension control motor for driving the same independently of the machine drive generally, a separator plate for separating the upper and lower course of the slit tubular fabric as it passes to the rejoining means, a pair of photoelectric

scanning heads responsive to the passage of the stripes on the two sides of the separating plate, a control circuit responsive to the scanning heads for producing an error signal corresponding to the lead of the stripes on one side of the separating plate as compared with those on the other, and means controlled by the control circuit for varying the speed of the said tension control motor to vary the tension on the course engaged thereby to register the stripes.

5. A stripe matching machine according to claim 4, comprising also adjustable means for driving the said tension control motor at a predetermined selected speed ratio to the machine drive generally, and in which the said means controlled by the said control circuit comprises means for varying said ratio in response to said 15 error signal.

6. A stripe matching machine according to claim 5, in which the means for varying the said ratio comprises a tension control motor field winding and means controlled by the control circuit for varying the current through said field winding.
